UNITED STATES PATENT OFFICE.

JAMES M. TAPLEY, OF CHARLESWOOD, MANITOBA, CANADA.

CRANK CASE FOR INTERNAL-COMBUSTION ENGINES.

Application filed November 18, 1922. Serial No. 601,927.

To all whom it may concern:

Be it known that I, JAMES M. TAPLEY, a citizen of the United States, and a resident of Charleswood, Manitoba, Dominion of Canada, have invented certain new and useful Improvements in Crank Cases for Internal-Combustion Engines, of which the following is a specification.

This invention relates to crank cases for internal combustion engines.

The present invention more particularly relates to crank cases used for internal combustion engines employed on motor vehicles and has for its object to provide means whereby the sediment collected in a crank case may be quickly and thoroughly removed without the removal of the crank case.

It is also an object of the invention that the crank case be adapted to be employed in an efficient manner as a retainer for lubricating oil which may be used for lubricating the engine cylinder and associated parts through the so called "splash system."

Other objects, and objects relating to details of construction, combination and arrangement of parts will hereinafter appear.

The invention is illustrated by way of example in the accompanying drawings, in which:—

Figure 1 is a longitudinal sectional view of a crank case when applied and showing the associated crank shaft in side elevation.

Figure 2 is a view in side elevation of a crank case constructed in accordance with the present invention.

Figures 3 and 4 are sectional views taken substantially on the lines 3—3 and 4—4 respectively of Figure 1.

Referring to the drawings more particularly, S indicates generally the crank shaft of an internal combustion engine, R the connecting rods associated therewith, and C the crank case of the present invention.

The crank case C more specifically consists in a single casting comprising an elongated plate 10 corresponding in dimensions to the opening in the bottom of engine housing to which the crank case is to be applied.

The plate 10 is provided with a plurality of depressed sections to provide the compartments 12 to serve as reservoirs for lubricating oil. The depressed sections 11 are preferably arcuate in cross section, Figure 3. The compartments communicate with each other through passages provided by

the tubular formation 13 formed with the casting.

The tubular formation 13 communicates with the bottom portion of each compartment 12 and the space occurring between plate 10 and the tubular portion at points between adjacent arcuate depressed sections is closed by the integral portions 14. The tubular formation 13 is slightly extended at the forward end of casting as at 15, and within the tubular formation there is positioned a rod 16 provided with a head 17 at its rear end which corresponds in diameter to the interior diameter of tubular formation. The other end of the rod may be threaded and carry a bushing, said bushing comprising a head 18 and a reduced threaded portion 18' which is threaded into the associated end of extension 13 so that a tight closure of the extension may be had. The rod also carries a plurality of washers 19, one occurring between each of the compartments 12 and adapted to effect a closure of the passage formed by the tubular formation 13. The washers 19 are held in proper spaced relation by sleeves 19' and these sleeves are clamped between the bushing 18 and head 17.

In the use of the present device, the same may be secured to the ordinary housing of an internal combustion engine, as illustrated in Figure 1 of the drawings. The different compartments 12 may be filled with a suitable lubricating oil and these compartments may be brought into proper alignment as illustrated so that the crank shaft of the associated engine will strike the oil during rotation thereof and splash the same for lubricating the internal walls of the cylinders and the piston heads. The tubular formation 13 to a certain extent aids in agitating the oil within the chambers 12 for lubricating the parts of the associated engine, which is thought to be obvious.

When it is desired to drain the oil from the different compartments 12, the rod 16 together with the sleeves 19' and washers 19 are removed and the oil permitted to run from the compartments through the openings formed by said tubular formation. Upon removing the rod the washers or collars 19 will draw therewith sediment which may have collected in the different compartments 12 and in this way cleaning the crank-case. The casting provided by this invention is sometimes referred to as an "in-

spection plate," however, in the present application it has been designated as a crank-case.

While I have shown and described the preferred form of my invention, I wish it to be understood that I am aware of the fact, that the construction, combination and arrangement of parts may be changed by those skilled in the art without departing from the spirit of the invention, as indicated by the appended claims.

I claim:

1. In combination with an engine, a crank-case having compartments extending transversely thereof and communicating through different passages, said passages being in longitudinal alignment, a rod extending through said passages and having washer means for closing the passages between said compartments.

2. In combination with an engine, a crank-case having compartments extending transversely thereof and communicating through different passages, said passages being in longitudinal alignment, a rod extending through said passages and having washer means for closing the passages between said compartments, said rod also being adapted when withdrawn from the crank case to permit liquid within the different compartments to drain from the crank case.

3. In combination with an engine, a crank case having compartments extending

transversely thereof, and communicating through aligned passages, a rod extending through said passages of smaller diameter than the passages, and means carried by the rod whereby the passages may be closed, for the purpose described.

4. In combination with an engine, a crank case having compartments extending transversely thereof and communicating through aligned passages, and an end compartment having a passage extending through its outer wall, whereby to drain the crank case and the last-named passage being in longitudinal alignment with the first-named passages, a rod extending through the different passages and carrying means whereby said passages may be closed, and means for locking the rod in its applied position.

5. The combination with an engine, a crank case having transverse compartments communicating with each other through aligned passages, and an end compartment having a passage in its outer wall adapted to drain said crank case and also in longitudinal alignment with the first-named passages, a rod extended into said passages, means carried by the rod adapted to close each of the passages, and a nut threaded upon the one end of said rod and adapted to be threaded into the associated end of the crank case, whereby to lock the rod against removal.

JAMES M. TAPLEY.
